FLARE

Starling Winters, Englewood, N. J.

Application October 11, 1944, Serial No. 558,231

3 Claims. (Cl. 102—37.1)

(Granted under the act of March 3, 1883, as
amended April 30, 1928; 370 O. G. 757)

1

The invention described herein may be manufactured and used by or for the Government for governmental purposes without the payment to me of any royalty thereon.

This invention pertains to flares.

A purpose of the invention is to provide a flare for use as a defense against hostile aircraft.

Another purpose of the invention is to provide a flare which will hover in the air while it burns and illuminates hostile aircraft.

A further purpose is to provide a hover flare which has a self-contained motor for keeping it at a predetermined altitude.

Other purposes will become apparent from the following description and drawings.

In defending against bombing raids by hostile aircraft, one method has been to have a great many searchlights on the ground for illuminating the attacking planes for the anti-aircraft guns and also for obscuring the vision of the airplane personnel by the high intensity illumination from the searchlights. An unusually large number of searchlights employed in such defended areas lessens the risk of complete neutralization of anti-aircraft defense, whereas in those areas where only a few searchlights are employed, attacking hostile fighter planes may put the searchlights entirely out of action before the bombers begin their runs over the target.

For the defense of areas where it is not possible to employ a saturation of searchlights against attacking aircraft, it is possible to achieve a similar effect by use of the hover type of flare shown and described herein. It is intended that a sufficient number of hover flares may be projected from infantry mortars to a height of 2000 to 5000 feet, for illumination of attacking aircraft without disclosing the location of the mortars.

In the drawings,

Figure 1 is a vertical sectional view of the projectile comprising a hover flare,

Figure 2 is a sectional view taken along the lines 2—2 of Fig. 1,

Figure 3 is a sectional view taken along the lines 3—3 of Fig. 1,

Figure 4 is a sectional view taken along the lines 4—4 of Fig. 1,

Figure 5 is a top view of the flare with wings extended,

Figure 6 is a sectional view taken along the lines 6—6 of Fig. 5,

Figure 7 is a sectional view taken along the lines 7—7 of Fig. 5,

Figure 8 is a front elevation of one extended wing,

2

Figure 9 is a sectional view taken along the lines 9—9 of Fig. 1,

Figure 10 is a sectional view taken along the lines 10—10 of Fig. 1,

Figure 11 is a sectional view taken along the lines 11—11 of Fig. 1 and

Figure 12 is a fragmentary view taken along the lines 12—12 of Fig. 11.

The anti-aircraft hover flare consists of a high intensity flare arranged to be projected from a mortar at maximum elevation to a predetermined height before starting to burn.

As shown in Figure 1, the flare consists of a hollow cylindrical base portion 13 forming a tail charge holder, surrounded by a plurality of annular shaped propelling charges 14, and a plurality of ports 15 connecting the interior of the cylindrical base 13 with the propelling charges 14. Inside the base portion 13 is a propelling cartridge 16 containing a charge 17 adapted to be ignited by a percussion primer 18 having a booster charge 19. Thus the flare is dropped into a mortar with the primer 18 downward and the primer 18 is fired by impact as it hits the firing pin inside the bottom of the mortar. The primer 18 ignites the booster 19 which ignites the charge 17, resulting in a flash through the flash holes or ports 15 igniting the propelling charges 14. The number of propelling charges 14 is determined by the height to which it is desired to shoot the flare. The explosion of the propelling charges causes the flare to be propelled out of the mortar into the atmosphere.

The flare has two wings or vanes 20 and 21 which are arranged to pivot on the fixed pivot pins 22 and 23 as shown in the drawing. A cylindrical intermediate body portion 24 has slidably mounted on its exterior a cylindrical vane-extending sleeve 25 having a pair of ears 26 and 29 at its upper end against which a vane-extending coiled spring 27 presses so as to urge the slider 25 upwardly. A pair of vane-extending links 28 and 29 are pivotally connected between the ears 26 and 29 and the pivots 31 and 32 on the vanes 20 and 21 respectively. Thus it is seen that as the slider 25 moves upwardly, it carries the links 28 and 29 upwardly and thus causes the vanes 20 and 21 to be rotatably extended from their position approximately parallel to the axis of the flare, to one approximately perpendicular to the axis and extending in opposite directions as shown in Figure 1. However the flare is placed in the mortar with its wings or vanes 20 and 21 folded close to its sides as shown in the full lines 55 in Fig. 1. The rapid movement of the flare as

it is propelled upwardly into the air causes the wind resistance to be so great as to prevent the wings 20 and 21 from unfolding until the flare has reached the top of its flight at which point the flare has ceased to move upward, and there is no wind resistance to prevent the spring 27 from causing the vanes 20 and 21 to unfold and extend outwardly.

At the top of the flare is a cylindrical flare body casing 33 surmounting a flare motor body 34, both having an outside diameter slightly less than the inside diameter of the mortar, so the flare can easily slide into the mortar. A flat partition 77 separates the casing 33 from the body 34. There is a central flare-igniting flash tube 35 passing through both the casing 33 and the motor body 34. The upper end of the flash tube 35 leads to a disk-shaped windshield-ejecting and flare igniting charge 36. In the hollow cylindrical casing 33 is placed a suitable illuminating composition 37. A rounded nose or windshield 38 is pressed over the top edges of the casing 33, and has a disk base 76.

A flare motor in the motor body 34 causes the flare to rotate about its axis by the reaction of burning gases escaping from the motor body through divergent nozzles 39 and 40 as seen in Figure 11, which are arranged to discharge the burning gases substantially tangentially as shown, thereby causing the rotation. The flared divergent shape of the nozzles 39 and 40 enables a large part of the heat energy of the gases to be converted into kinetic energy for rotation. The gases are fed to the bases 41 and 42 of the nozzles by means of the nozzle feed tubes 43 and 44 which project radially outward in opposite directions from the chamber 45 in the upper portion of which is placed a match composition 46 for igniting a flash charge 47 which ignites the flare motor charge 48. A protective moisture-proof paper match seal 75 covers the lower surface of charges 46 and 47. The charge 48 fills the chamber 49 and the chambers 50 and 51, the ports 52 and 53 serving to connect the chambers containing the charge 48. The charge 48 may be made of any suitable rocket composition, and upon being ignited it gives off the gases which are allowed to escape through the nozzles 39 and 40 as described, thereby causing the flare to rotate. The nozzle feed tubes 44 and 43 have clean-out plugs 64 and 65 at their outer ends.

A firing pin 54 having a serrated striker point 55 and a coiled striker spring 56 around its shank, is slidably arranged for longitudinal movement in the central bore 57 in the intermediate body portion 24 with its point 55 pointing upward toward the match composition 46. The firing pin 54 has a lower extension 58 carrying a pair of members 59 and 60 on a pivot 61, the outer ends of the members engaging two oppositely disposed apertures 62 and 63 in the sides of body portion 24. Thus, since the members 59 and 60 are each slightly longer than the radius of the outside diameter of the body portion 24 at this point, the toggle action prevents the firing pin 54 from being pushed upward by the spring 56 until the sleeve 25 has moved upward a sufficient distance to uncover the ports 62 and 63, permitting the ends of the members 59 and 60 to pass through the said ports.

The flat wing portions of the two vanes 20 and 21 are constructed of sheet metal or other suitable material, as shown in Figure 5 and each vane is bent upwards from its center outward by a positive dihedral angle of five degrees. Figures 75

6 and 7 show the cross sectional shape of the vanes at the sections indicated. As shown in Figures 9, 10 and 11, the flare motor body 34 has a pair of vertically disposed channels 67 and 68 in which the pivoting portions of the vanes and the vane extending links 28 and 29 move and rotate as the vanes are moved from their folded position along the sides of the flare to their extended position at the top of the vertical flight.

10 A safety pin 70 having a pull ring 71 is inserted through a pair of oppositely disposed holes 72 and 73 formed in the intermediate body portion 24 and also through a transverse opening 74 drilled through the shank of the firing pin 54, as shown in Figures 1 and 2. Thus the inserted safety pin 70 prevents the firing pin 54 from being released against and igniting the primer 46 even though the vanes 20 and 21 should accidentally be extended before the desired time, since the safety pin 70 is not withdrawn until the flare is ready to be projected into the air.

When the flare is to be fired, the vanes are held closely against its sides and the flare is inserted about one quarter of its length into the 25 mortar, tail first. The safety pin 70 having been pulled out, the flare is allowed to drop into the mortar tube until its tail percussion primer 18 strikes against an upward pointing firing pin mounted inside the base of the mortar tube, igniting the primer 18. The booster 19 is then ignited and in turn ignites the charge 17, resulting in a flash through the holes 15 igniting the propelling charges 14 and shooting the flare out of the 30 mortar. As the flare reaches the desired height 35 it stops ascending and the vanes 20 and 21 extend radially outward. As they do so, the firing pin 54 is released against the match composition 46 igniting it and the flash charge 47. The motor charge 48 is ignited thereby, and the burning 40 gases emerge forcefully out of the nozzles 39 and 40, causing the flare to rotate. At the same time the flash from the charge 47 has extended up through the tube 35 and ignited the charge 36, the resulting gas pressure forcing off the 45 windshield 38. The flare composition 37 is ignited and serves to give off intense illumination to the sky and to objects such as hostile airplanes. The helicopter effect of the rotating vanes 20 and 21 causes the flare to hover for quite some time until 50 the motor charge 48 is consumed, when the flare drops slowly to the earth where it can be refilled and reused.

The various charges used in the flare are of the well known compositions familiar to the pyrotechnic art for the several purposes described.

While the foregoing specification sets forth the invention in specific terms, it is to be understood that numerous changes in the shape, size, arrangement and materials may be resorted to without departing from the spirit and scope of the invention as claimed herein.

I claim:

1. An aerial device comprising a cylindrical flare body surmounting a cylindrical flare motor body, propeller blades pivoted on said flare motor body and foldable within the extremities of said flare motor body, resilient means constantly urging said blades to open position transversely to the longitudinal axis of said device, said means operative to open said blades only at a substantially zero value of aerodynamic pressure on the blades, jet propellant means in said motor body to rotate said device about its longitudinal axis, spring-pressed means to initiate the jet propellant means, and a detent for the spring-pressed

means connected with the propeller blades, for disarming the spring-pressed means on distension of the propeller blades.

2. The invention of claim 1, said spring-pressed means comprising a firing pin in a tube, perforations in the tube, and a toggle means on the firing pin extending into the perforations, and said device comprising a sleeve surrounding the tube and normally closing the perforations.

3. An aerial device comprising a cylindrical flare body containing flare material surmounting a cylindrical flare motor body containing propellant material, jet orifices in said motor body arranged to exert a torque for rotation of said device about its longitudinal axis, radial slots in said motor body, propeller blades pivoted in said slots and having spring-pressed thrust links distending said blades at a predetermined aerodynamic pressure, a tube containing a spring-pressed firing pin, said tube affixed to and extending rearwardly from said motor body and in axial alignment with a flash tube extending through said motor body and said flare body, a primer in said motor body communicating with said propellant and said flare materials and aligned with said firing pin, aligned perforations

in said tube remote from said motor body, a toggle on the firing pin extending into said perforations, a sleeve concentrically mounted on said tube and normally covering said perforations, said sleeve attached to said thrust links whereby the perforations are uncovered on distension of the blades to neutralize the holding action of the toggle.

STARLING WINTERS.
